UNITED STATES PATENT OFFICE.

FRANK E. FREDERICKS, OF BAYS, OHIO.

STUFFING-BOX.

SPECIFICATION forming part of Letters Patent No. 732,291, dated June 30, 1903.

Application filed October 31, 1901. Serial No. 80,708. (No model.)

To all whom it may concern:

Be it known that I, FRANK E. FREDERICKS, a citizen of the United States, residing at Bays, in the county of Wood and State of 5 Ohio, have invented a new and useful Stuffing-Box, of which the following is a specification.

My invention relates to improvements in stuffing-boxes; and the objects of my improvement are, first, to provide a stuffing-box in which all the parts subject to wear are easily removed and inexpensively replaced; second, to provide an aperture in said stuffing-box large enough to permit the withdrawing of the 15 sucker-rods from the well without at the same time removing the stuffing-box; third, to provide lever-rests on the follower. I attain these objects by the mechanism illustrated in the accompanying drawings, in which—

20 Figure 1 is a vertical section of the entire stuffing-box; Fig. 2, a top view of the follower; Fig. 3, a view of the lower part of the follower removed, through which a polish-rod operates; Fig. 4, a view of the bushing or 25 ring through which the polish-rod operates in bottom of stuffing-box; Fig. 5, a view of the cup which contains the packing and into which the other parts are fitted.

A is the cup or outside of the stuffing-box. 30 The cup has its lower end integral with a downwardly - projecting, interiorly - screw-threaded annular extension of less diameter, forming thereby a coupling or nipple and which also forms the annular shoulder E on 35 the inner face of the cup, at the lower end thereof. The shoulder is adapted to support the ring or bushing D, and the screw-threaded coupling or nipple is for the purpose of connecting the stuffing-box in position to the 40 tubing (not shown) when used in connection with the pumping of a well. The opening in the coupling and cup is of such diameter that when the stuffing-box is used in connection with pumping a well the rods and valve (not 45 shown) can be elevated through the cup without its removal, such movement carrying the bushing or ring D therewith, or, in other words, the rods and valve can be pulled through the stuffing-box without removing it.

50 B is the upper part of the follower, carrying on its rim the lever-rests F F.

C is the lower part of the follower, with

threads cut around its upper part by which it is attached into the upper part of the follower B, and thus held securely.

55

The follower is made of two parts, for the reason that in stuffing-boxes the lower part of the follower invariably wears out first, making it necessary to replace an entirely new follower, whereas by constructing the follower 60 of the two parts B C, as shown, it is only necessary to replace the lower part C, thereby obtaining a saving in cost of about one-half, as the entire follower does not have to be replaced.

65

This stuffing-box is intended to be used wherever a stuffing-box is applicable. When used in pumping a well, it is attached by means of the threads at the lower end of the cup A to a T or other connections at top of tubing. (Not shown.) Through it (and through the apertures in D and C) a polish-rod works to lift the fluid from the well. Between D and C, within the cup A and around the polish-rod, a packing of rubber, hemp, &c., is 70 placed on which the follower rests, held in place by means of a lever (not shown) resting upon the lever-rests F F, completely preventing the escape of fluid around the polish-rod.

75

What I claim as my invention, and desire to 80 secure by Letters Patent, is—

1. In a stuffing-box, a cup provided with an inwardly-extending shoulder and means for securing it in position, a follower arranged in the cup and consisting of a pair of detachable 85 and fixedly-adjustable telescopic sections, one partly inclosing the other, and a bushing mounted upon said shoulder.

85

2. In a stuffing-box, a cup, a follower arranged therein and consisting of a pair of detachable and fixedly-adjustable telescopic sections 90 engaging with each other, and a bushing arranged within said cup below the lower of said sections.

90

3. In a stuffing-box, a cup, means integral 95 with the cup for securing it in position, a follower mounted in the cup and consisting of a pair of detachable and fixedly-adjustable telescopic sections, the upper of said sections formed with lever-rests, and a bushing arranged below said lower section of the follower.

100

4. In a stuffing-box, a cup, a follower mounted therein and consisting of a pair of

detachable and fixedly-adjustable telescopic sections, a bushing arranged below said lower section of the follower, and a suitable packing interposed between said bushing and the lower section of the follower.

5. In a stuffing-box, a cup, a follower arranged therein and consisting of an interiorly-screw-threaded annular upper section and an exteriorly-screw-threaded annular lower section, said sections adapted to telescope one within the other, and a bushing arranged in the cup below the lower section of the follower.

6. In a stuffing-box adapted for use for 15 well-pumping machinery, a cup provided with openings of two different diameters, each of which is of such size as to permit of the passage therethrough of the pumping-valve and

its rod of the machine, and a suitable packing arranged in said box.

7. In a stuffing-box adapted for use for well-pumping machinery, a cup provided with openings of two different diameters, each of which is of such size as to permit of the passage therethrough of the valve and valve-rods 25 of the machine, a shoulder formed at the top of said portion of smaller diameter, a bushing mounted upon said shoulder, and a suitable packing arranged in said cup.

In testimony whereof I have signed my 3c name to this specification in the presence of two subscribing witnesses.

FRANK E. FREDERICKS.
